UNITED STATES PATENT OFFICE.

JOHN SOMMER, OF PEORIA, ILLINOIS.

TILE-PLACING ATTACHMENT FOR DITCHING MACHINES.

Application filed June 21, 1920. Serial No. 390,471.

To all whom it may concern:

Be it known that I, JOHN SOMMER, a citizen of the United States, residing at Peoria, in the county of Peoria and State of Illinois, have invented new and useful Improvements in Tile-Placing Attachments for Ditching Machines, of which the following is a specification.

This invention has reference to a tile placing attachment for ditching or excavating machines, which is particularly applicable to wheel type machines.

One of the objects of the present invention is to provide a tile placing attachment for ditching or excavating machines which will facilitate the laying of the tile in any soft ground which is subject to cave-in, and also in ground containing quicksand; whereby, the tile may be pushed into and held in place and a contiguous joint made with the next adjoining tile, and so held, even in the event of cave-in.

The invention has for a further object to provide a tile placing attachment for ditching machines including a means for supporting a tile section, and retractable means for pushing said tile section into contiguous relation and in axial alignment with the preceding laid tile sections and holding the same in such position.

A further object of the invention is to provide a tile placing attachment for ditching or excavating machines intended for use in muddy ground, as well as ground containing quicksand, and subject to cave-in; such attachment comprising a housing connected to and movable with the excavating elements and in the ditch formed thereby; said housing constituting a movable curbing to retain the walls of the ditch during the placing of the tile, and means operable in the said housing for pushing the tile sections into place, and for holding the same in place as the machine moves forward.

A further object of the invention is to provide the housing with a removable chute thru which gravel may be conveyed to cover and surround the tile sections when placed in ground containing quicksand; said chute formed with a shield at its lower end to insure a proper distribution of gravel over and around the tile sections, and thereby protecting the latter against cave-in, during the movement of the machine, and until the said tile sections have been protected by gravel.

That the invention may be more fully understood, reference is had to the accompanying drawings forming a part of this description, showing a preferred embodiment of the invention, in which;

Fig. 1 is a side elevation of my improved tile laying attachment the same being associated with a ditching machine of the wheel type, only a sufficient amount of the latter being shown to show the relation of the tile laying attachment thereto;

Fig. 2 is a view somewhat similar to Fig. 1, with the exception that the tile laying attachment is shown in vertical section, and the tile section pushing means has been retracted and tile section placed in position to be pushed against the next contiguous section and in axial alignment therewith;

Fig. 3, is an end view looking in at the left-hand end of Fig. 1.

Fig. 4, is a vertical cross-section as the same would appear taken on the line 4-4 Fig. 1 looking in the direction of the arrows in said figure;

Fig. 5, is a detailed cross-section in plan as the same would appear if taken on the line 5-5 Fig. 1 looking in the direction of the arrows in said figure.

Fig. 6, is a detailed cross-section as the same would appear if taken on the line 6-6 Fig. 2 looking in the direction of the arrows in said figure; and

Fig. 7, is a detailed cross-section as the same would appear if taken on the line 7-7 Fig. 2 looking in the direction of the arrows in said figure.

Like characters of reference denote corresponding parts throughout the figures.

Ditching or excavating machines of the wheeled type are well known to those skilled in the art, and I therefore, have only shown so much of such a machine as will be necessary to illustrate the connection of my tile laying attachment thereto. The digging wheel of such machines is designated by the dotted lines 1 provided with the annular toothed rims 2 engaged by driving gear wheels 3, carried on a shaft 4, operated in any suitable manner from the motive power carried by the machine. These machines have a supporting framework, which in this instance is designated by the beams 5, 6 and 7, and it is to these beams that my tile laying attachment, to be described, is suitably connected.

Ordinarily the ditches dug by the ditching

2
or excavating machines, in which the drain tile is laid, is in ground where the danger of a cave-in of the side walls of the ditch is not to be seriously considered, and the 5 tile may be laid by the workmen with little or no difficulty and without the need of such an attachment as herein shown and described. However, ground is often encountered in which the ditches are dug which is 10 very muddy, or which contains considerable quicksand. In either event the laying of the tile during the digging of the ditches or thereafter, is done with considerable difficulty, by reason of the fact, that cave-ins 15 will occur before the tile sections can be properly laid and placed in juxtaposition to each other, and incidents are on record, where, during the laying of the tile sections in such ground, cave-ins have occurred, and 20 the pressure has been so great upon the tile sections that they were separated axially, the ground forcing the tile sections apart and entering therebetween, destroying communication between the said tile sections. 25 My attachment aims to overcome the possibility of the cave-in of the walls of the ditches during the placing of the tile sections, and makes it possible to so place the 30 said sections in juxtaposition to each other that they are retained in place and cave-ins will have no material effect thereon to separate the same. Further, when ground is encountered containing quicksand, my attachment provides for the introduction of gravel 35 into the ditch on which the tile sections may be laid and for covering and surrounding said tile sections with gravel to protect the same against caving in of the walls of the ditch.

40 The attachment includes a housing made up of the opposite side walls 8, connected by the curved bottom wall 9 and the rear vertical wall 10, the latter stopping short at the bottom of the housing as at 11 to provide an opening in the rear end of the housing as shown at the bottom in Fig. 2, thru 45 which is pushed the tile sections A, as will be more fully explained. The forward ends of the side walls 8 are arranged to have a suitable detachable connection with the beams 7 forming a part of the frame work of the machine, whereby the housing is drawn by the machine and thru the ditch cut by the ditching wheel 1. In other words, 50 the housing trails the ditching wheel with the curved bottom 9 of the housing, preferably moving on the bottom of the ditch and conforming to the cross-section thereof, see Figs. 3 and 4. The said housing, as will be observed looking at the cross-sectional views 55 3 and 4 constitutes a movable curbing to retain the walls of the ditch during the placing of the tile, the tile placing means being operably carried within the housing, as 60 will be explained.

The tile placing or pushing means comprises the bar or rod 12 provided with the head 13 at its rear end to which is connected the rearwardly extending tile rest 14; the said bar or rod near its rear end and forward of the head 13 is connected with a cross-frame 15 having journaled thereon wheels or rollers 16 movable on rails 17 suitably secured to the curved bottom 9 of the housing, see Figs. 2 and 6. Said bar or rod 12 at its forward end has connected thereto a suitable coupling 18 on which are journaled wheels or rollers 19 movable in the substantially channel beam rails 20. Making the rails 20 in the form of channel beams, will prevent up or down movement of the wheels or rollers 19, and confines the forward end of the bar or rod 12 in all of its movements. The rails 20 are connected to the upstanding supports 21, shown in this 5 instance to be angle iron beams and at a suitable point, see Fig. 4, to the said beams 5 and 6 of the frame of the machine, see Fig. 2. The lower ends of these supports are connected by the cross piece 22 to the 10 curve bottom 9, see Fig. 7. Secured to the supports 21 at or near the lower ends thereof are the short upright supports 23 in which are journaled a short cross shaft 24 carrying the double sheave wheel 25, see Figs. 2 and 7. 15 As a means for reciprocating the bar or rod 12, I provide the double sheave wheel 25, also the fast and loose sheave wheels 26 and 27 respectively carried by the cross shaft 28, journaled on the frame work of 20 the machine, the said shaft 28 having keyed thereon the sprocket wheel 29 driven by a sprocket chain 30 from a sprocket wheel 31 on the shaft 4. 32 denotes a cable passing over and around the sheave wheel 26 keyed 105 to the shaft 28 down and around one section of the double sheave wheel 25 and has its end connected to the coupling 18 secured to the forward end of the bar or rod 12. The free end of this cable has a hand-hold 110 33 connected thereto. 34 denotes a cable passing over the sheave wheel 27 which is loose on the shaft 28 and down and around the other section of the sheave wheel 25 and has its end connected to the head 13 115 on the end of the bar or rod 12. The free end of this cable has connected thereto the hand-hold 35. The means employed for moving the bar or rod 12 provides for the same to be moved rearwardly with the assistance of the source of power on the machine and for manually returning or moving the said bar or rod forwardly. It is understood that the shaft 28 is connected to and operated from the source of power on 120 the machine and the driving connections may be such that the shaft 28 will be operated, both when the machine is standing still, as well as moving. Assuming the shaft 28 to be rotating in the direction indicated 125 130

by the arrows in Figs. 1 and 2, if the operator pulls down on the hand-hold 33 the frictional engagement of the cable 32 with the sheave wheel 26 keyed to the shaft 28 will impart movement to the cable 32 such as will move the bar or rod 12 from its position shown in full lines in Fig. 2 to the position shown in the dotted lines in Fig. 1. To reverse the movement of the bar 10 or rod 12 and return it to the position in full lines in Fig. 2, the operator need only pull on the hand-hold 35 causing the cable 34 to be moved in the direction to return the bar or rod 12 to its normal or initial 15 position. It is preferable to employ the power of the machine to assist in moving the bar or rod 12 when placing a tile section, and employing a yielding means such as is produced by the cable 32 and the sheave 20 wheel 26, a tile section may be moved and held in juxtaposition to the next contiguous section as the machine is moved forwardly to prevent displacement of the then placed tile section should the walls of the ditch 25 cave in. The tile sections A are successively placed on the tile rest 14 connected with the head 13 in the manner shown in Fig. 2. The housing has a sufficient width to permit a workman to stand therein to 30 receive and place the tile sections on the rest, in the manner shown.

The attachment, as now described, is useful when the machine is operating in muddy ground void of quicksand conditions, but 35 which is subject to cave-in, the side walls 8 of the housing acting as a curbing to retain the side walls of the ditch and permit the placing of the tile sections A on the bottom of the ditch, the said tile sections being 40 pushed out thru the opening in the rear end of the said housing, as will be understood.

To provide for the laying of the tile sections in ditches where quicksand is 45 encountered, I employ a chute 36 formed with a hopper 37 at its upper end and with a semi-circular rearwardly extending shield 38 at its lower end. This chute is arranged for detachable connection with the rear end 50 wall of the housing, see Figs. 1 and 3.

To use the chute, it is filled with gravel, represented by the dotted lines in Figs. 1, 2 and 3 which forms a bed on the bottom of the ditch on which the tile is laid and 55 then completely surrounds the tile, so as to protect the latter against the quicksand action and any cave-in of the walls of the ditch. In Fig. 2 a tile section A is shown in place and protruding thru the opening 60 in the rear end of the housing, part of the tile within the housing and part without, but protected by the shield 38 of the chute. Here it will be seen that the gravel has formed a bed for the said section of tile, 65 and covers all of that portion protruding

without the housing and has spread within the housing almost to the forward end of the tile section. At this point a new tile section is placed so as to be moved in juxtaposition to the tile section lying part within and part without the housing, and when the new section has been so placed the forward movement of the machine will allow the gravel discharged from the chute to spread over and around the newly placed 70 tile section in the manner shown in connection with the last placed tile section in Fig. 2. It is to be understood that the placing of the said tile sections when using the chute 36 is so timed that a bed of gravel 75 is provided for the said sections, as shown in Fig. 2, so as the machine moves forwardly there can be no tipping of the said tile sections which would dislodge the same and prevent axial alignment of the next and 80 succeeding tile sections.

What I claim is:—

1. In a machine of the character described, in combination, power means for digging a ditch, movable means for supporting tile sections, means for utilizing the power of the digging machine to push the tile sections into place, and other means for returning said pushing means to tile receiving 95 position.

2. In a machine of the character described, in combination, ditch digging means, an attachment to trail the digging means in the ditch, means within the attachment to support tile sections by insertion of such means within the tile sections, and means to move said support to push the tile sections endwise into place in the ditch, and into 100 abutting relation with other sections.

3. In a machine of the character described, in combination, ditch digging means, an attachment to trail the digging means in the ditch, the same having an opening thru which are pushed tile sections, means within the attachment to support tile sections by insertion of such means within the tile sections, and means to move said support to push the tile sections thru the opening in 105 said attachment and into place in the ditch.

4. In a machine of the character described, in combination, means for digging a ditch, means for supporting tile sections, means for pushing the said tile sections into place in the ditch and for retaining the same in position as they are placed, and means by 110 which gravel may be introduced into the ditch to provide a bed for the tile sections and to cover the same.

5. In a machine of the character described, in combination, ditch digging means, an attachment to trail the digging means in the ditch, means within the attachment to support tile sections, means to move said support to push the tile sections into place in 115 the ditch and for retaining the same in position as they are placed, and means by which gravel may be introduced into the ditch to provide a bed for the tile sections and to cover the same.

- tion as they are placed, and means on the attachment by which gravel may be introduced into the ditch to provide a bed for the tile sections and to cover the same.
- 5 6. In a machine of the character described, in combination, means for digging a ditch, a housing forming a movable curbing for the ditch connected to trail said digging means, and tile placing means operably carried in said housing adapted to place and positively retain the tile in position as they are placed.
- 10 7. A tile placing attachment for excavating machines, comprising a housing arranged for connection with the machine, a reciprocal tile support horizontally disposed within said housing, and means to move said support to place a tile section in position and return said support to tile receiving position.
- 15 8. A tile placing attachment for excavating machines, comprising a housing arranged for connection with the machine, said housing having an opening thru which are pushed the tile sections, a chute attachable to said housing and having an extension shield, a reciprocal tile support within said housing, and means to move said support to place a tile section in position and return said support to tile receiving position.
- 20 9. In a machine of the character described, in combination, means for digging a ditch, and means for placing tile sections in abutting positions in said ditch and for positively retaining the same in such position as they are placed.
- 25 10. In a machine of the character described, in combination, means for digging a ditch, and reciprocally arranged means for placing tile sections in abutting positions in said ditch and for holding the said sections in such position as they are placed.
- 30 11. In a machine of the character described, in combination, means for digging a ditch, means for placing tile sections in abutting positions in said ditch, and means for moving said placing means to position said tile and for positively retaining the same in position as the machine is moved forward.
- 35 12. In a machine of the character described, in combination, means for digging a ditch, reciprocally arranged means for placing tile sections in abutting positions in said ditch, means to move said placing means in one direction to place tile and for positively retaining the same in position as the machine is moved forward, and means to retract said placing means.
- 40 13. In a machine of the character described, in combination, means for digging a ditch, means for supporting tile sections by insertion of such means within the sections, and means for pushing the said tile sections into place in the ditch and for retaining the same in place.
- 45 14. In a machine of the character described, in combination, means for digging a ditch, means for supporting tile sections, and means for pushing individual tile sections into place, each section in abutting relation to a preceding section, and for positively retaining each section as it is placed and during a forward movement of the machine.
- 50 15. In a machine of the character described, in combination, ditch digging means, an attachment to trail the digging means in the ditch, means within the attachment to support tile sections, and means to move said support to place the tile sections in abutting relation and to positively retain the same so placed during the movement of the machine.
- 55 16. In a machine of the character described, in combination, ditch digging means, an attachment to trail the digging means in the ditch, means within the attachment to support tile sections, and means reciprocally arranged in said attachment for moving said support to place the tile sections in abutting relation and to positively retain the same so placed during the movement of the machine.
- 60 17. In a machine of the character described, in combination, means for digging a ditch, a housing forming a movable curbing for the ditch connected to trail said digging means, and means within said housing for placing tile sections in abutting relation and for positively retaining the same so placed.
- 65 18. In a machine of the character described, in combination, means for digging a ditch, a housing forming a movable curbing for the ditch connected to trail said digging means, and means reciprocally arranged within said housing for placing tile sections in abutting relation and for positively retaining the same in position during the movement of the machine.
- 70 19. In a machine of the character described, in combination, ditch digging means, an attachment to trail the digging means in the ditch, the same having an opening thru which tile sections are placed in abutting relation, means within said attachment to move each tile section in place and for positively retaining the same in abutting relation as the machine is moved forward, and a chute on said attachment thru which gravel may be introduced into the ditch to provide a bed for said tile sections and to cover the same.

JOHN SOMMER.
